UNITED STATES PATENT OFFICE.

MONROE L. MELETIO, OF ST. LOUIS, MISSOURI.

VENDING MACHINE.

Application filed January 6, 1926. Serial No. 79,583.

My invention relates to a new and useful improvement in vending machines and more particularly to venders which are known as the profit-sharing type. In the so-called 5 profit-sharing type of vending machine, the customers inserts a coin and operates a lever. Wheels with characters on them are rotated and their position when they come to rest determines whether or not the customer receives one or more trade checks in addition 10 to the item purchased. In some jurisdictions these profit-sharing vending machines have been held to be gambling devices and their owners now have expensive machines on 15 their hands without any use for them since all sales attraction is lost if there is no result to the spinning of the character wheels.

With the foregoing conditions in mind, the principal object of my invention is to 20 provide an interchangeable front for profit-sharing vending machines that eliminates the element of chance in making sales.

Another object is to provide a card on 25 which each character represented on each wheel is given a meaning, said meaning fitting in any combination to form sentences.

With the foregoing and other objects in view, my invention consists in certain novel 30 features of construction and arrangement of parts, hereinafter more fully described and claimed, and illustrated in the accompanying drawings, in which—

Figure 1 is a perspective view of my improved vending machine.

Figure 2 is a rear view showing the cash-door removing arrangement.

Figure 3 is a fragmentary view of the fortune-telling card.

Figure 4 is a fragmentary perspective 40 view of the vending machine in its original form with provision for delivery of profit sharing.

The numeral 1 in the drawings indicates 45 a profit-sharing type of vending machine having mechanism therein for unlocking the delivery chute 2 and rotating the character wheels 3, 4, and 5, which mechanism forms no part of my present invention.

The coin chute 6 charges the profit-sharing 50 chute 7 to capacity with checks and when coins or additional checks are introduced for the operation of said machine they are by-passed through chute 8 into a reservoir 9. Profit-sharing chute 7 in the gambling 55 type of machine terminates in a pocket on the exterior of the front and extending into

the face, but, in the present non-gambling type of vender, I divert this chute interiorly of the machine, provide a flared skirt on the front which conceals the pocket, and provide a reservoir 10 to receive the profit-sharing checks and retain them when the mechanism of the device acts to make a delivery. A large door 11 is provided to permit the removal of the main drawer or reservoir 9 and a small relief door 12 is located adjacent to opening 10^a in reservoir 10 to permit the removal of such excess profit-sharing checks which in time accumulate in reservoir 10 to such an extent as to interfere with the proper operation of the machine.

Figure 4 is illustrative of the vending machine in its original form. The numeral 20 indicates the profit-sharing delivery pocket 75 in front 21. 22 is the lower portion of the profit-sharing delivery chute which is removed with front 21 to permit the positioning of the reservoir 10 and the diversion of the main portion 7 of the chute which is bent to the desired position by the application of the non-gambling type front 23. The front 21 is held in place by a series of studs (not shown) which are only accessible through the locked door 9 in the rear of 80 the machine. To effect the conversion into a non-gambling type machine heretofore described, the front 21 is removed and the front member 23 installed in its place as shown in Figure 1.

It should be understood that these machines are put out by distributors who lease them for periods of time. Certain territories have seasonal demands and it is frequently found to be a condition that a district which does a large business with these venders in one season allows the distribution of profit-sharing checks to the customers, while an adjoining district doing a large business at another season of the year forbids this distribution by interpreting it as gambling. It can be readily seen that with these conditions it is very advantageous to have interchangeable machines to meet these requirements, especially so where the initial cost of the device is great, as in the present instance.

The rotatable wheels 3, 4, and 5 are each provided with characters so indicated by numerals 13, 14, 15 and 16. In the gambling 110 type of machine, the arrangement of these characters under arrow 17 determines

whether or not there is any profit-sharing, and, if so, to what extent. This feature is a great sales producer and to incorporate it in my non-gambling vender I provide a card 18 which contains a list of each character on each wheel. This card 18 is adapted to be retained in frame 20 on the front of the vender and words 19 are printed with each character so that with any combination of the characters on wheels 3, 4, and 5 reference may be made to the similar characters on card 18 and the combination of words referred to will form a sentence which, in the present case, is shown as a fortune-teller. For example:—The combination indicated under arrow 17 in Figure 1 of the drawings is a bunch of cherries 14 on the first wheel, a plum 13 on the second wheel, and a bell 16 on the third wheel. Reference to the card gives the following fortune for this combination:—“You gain money by sincere effort but you do not appreciate your good fortune.”

It will be found that any possible combination of characters will form a sentence complete in itself which tells a fortune.

The application of my non-gambling equipment to a profit-sharing type of vending machine is very simple, constituting principally a change in the front of the machine which is merely locked on. The cost of making these interchangeable parts is very small and the additional use of the machine is comparatively great.

It is to be understood that minor changes in the size, form and construction of the various parts of my improved vending machine may be made and substituted for those herein shown and described, without depart-

ing from the spirit of my invention as expressed in the appended claims.

I claim:

1. An interchangeable front for a profit-sharing vending machine having a plurality of rotatable character wheels and a profit-sharing delivery chute, said front being so constructed that when it is applied to the vending machine it encloses and conceals said profit-sharing delivery chute and diverts the articles from said profit-sharing delivery chute within the vending machine, and a card on said front having words for each character on each of said wheels, said words being adapted to fit together in any combination indicated by said wheels to form a sentence.

2. A vending machine of the profit-sharing type having a profit-sharing delivery chute and an interchangeable front, said front being constructed to enclose said profit-sharing chute within said vending machine when applied thereto.

3. A vending machine of the profit-sharing type having a profit-sharing chute, a delivery pocket, and an interchangeable front, said front being constructed to conceal said delivery pocket when applied to said vending machine.

4. A vending machine of the profit-sharing type having a profit-sharing delivery chute and an interchangeable front, said front being constructed to enclose said profit-sharing chute within said vending machine when applied thereto, and divert its discharge within the machine.

In testimony whereof I hereunto affix my signature this 31st day of December, 1925.

MONROE L. MELETIO.
